CLAIM

The ornamental design for the container body, substantially as shown and described.

DESCRIPTION

FIG. 1 is a top, rear and left side perspective view of the container body;

FIG. 2 is a right side view thereof (the left side view is a mirror image);

FIG. 3 is a top plan view thereof;

FIG. 4 is a cross sectional view taken along the lines 4—4 of FIG. 2;

FIG. 5 is a front view of FIG. 1;

FIG. 6 is a rear view thereof;

FIG. 7 is a bottom plan view thereof; and,

FIG. 8 is a partial cross sectional view taken along lines 8—8 of FIG. 7.

The broken line showing in FIGS. 1-3, 5, & 6 is for illustrative purposes only and forms no part of the claimed design.
